United States Patent

Des. 235,551
Patented June 24, 1975

235,551

ELECTRICAL CONNECTOR

Paul "B" Derr, Middletown, Gilbert Douglas Ferdon, Hummelstown, and Robert George Harwood, Mechanicsburg, Pa., assignors to AMP Incorporated, Harrisburg, Pa.

Filed Sept. 29, 1972, Ser. No. 293,625

Term of patent 14 years

Int. Cl. D13—03

U.S. Cl. D26—1 A

FIG. 1 is a perspective view of an electrical connector showing our new design;

FIG. 2 is a front elevational view thereof;

FIG. 3 is a rear elevational view thereof;

FIG. 4 is a right side elevational view of FIG. 2;

FIG. 5 is a bottom plan view of FIG. 2; and

FIG. 6 is left side elevational view of FIG. 2.

We claim:

The ornamental design for an electrical connector, substantially as shown.
